DISTRIBUTION SYSTEM

Louis M. Potts, Evanston, Ill., assignor to Teletype Corporation, Chicago, Ill., a corporation of Delaware

Application July 20, 1942, Serial No. 451,577

22 Claims. (Cl. 178—1)

The present invention relates to telegraph message handling apparatus and more particularly to equipment for automatically preparing and routing strips of material bearing perforated or otherwise marked message matter to various signal transmitting apparatus.

At central offices there may be converged the principal trunk lines from a plurality of outlying or subsidiary stations at which messages originate for communication to other outlying or subsidiary stations through the central offices. Communication between any ones of a plurality of subsidiary stations and others is most efficiently handled by recording, in a perforated form, the message matter incoming from said stations and thereafter retransmitting said message matter to the respective destination stations when transmission lines are available. In order to facilitate this operation, incoming messages are recorded in one or more lengths of control forms, which are stored within portable containers or spools, pursuant to copending application Serial No. 451,576, filed on even date herewith. Thereafter said message containers are directed to retransmitting apparatus whence the messages perforated on the forms are repeated as electrical impulses over outgoing lines, and directed to the proper destination stations, according to the address or other information carried by the messages.

The principal object of the present invention is to provide a message distribution system and apparatus operating automatically to distribute the messages physically to signal transmitters associated with telegraph circuits extending to a plurality of subscribers to whom the messages may be addressed.

In the attainment of this and other objects, there is featured a strip preparing and carrier packaging apparatus which automatically marks and spools lengths of message bearing control forms, a conveyor apparatus which routes said strip to a certain retransmitting apparatus, according to its marked destination, and thereafter unspools said message and automatically inserts it into a retransmitting apparatus where the message contained thereon is translated into telegraphic signals.

Briefly, the invention employs an endless conveyor, along which there are arranged a plurality of signal controlled tape perforating machines each having electrical communication with an incoming line. Carriers are supplied to each one of the perforating machines and, as each incoming message is perforated upon a strip, it is wound into a coil and placed within one of the containers

with the address portion of the message remaining at the periphery so as to be visible to an operator. In order to obtain speed and economy advantages over manual distribution, means are provided for automatically placing the prepared message carriers or containers within predetermined compartments or storage spaces in the conveyor system which are destined for discharge at certain other stations along the conveyor, whereat all messages for the same or for related destinations are discharged. There the spool is unwound with the foremost part of the message entering a retransmitting apparatus and, as the tape is withdrawn from its container, the message thereon is translated into telegraphic signals and transmitted electrically to the designated station.

Among the novel features of the present invention, is the provision of apparatus associated with a conveyor or distributing system whereby, with a number of incoming line station equipments and a number of retransmitting apparatuses, a distribution arrangement may be made regardless of the physical location of said equipments and apparatus so that messages coming over any one or more receiving station apparatuses may be routed one after another to the transmitter apparatuses so as to avoid peak load conditions by utilizing all available line time and fully working the greatest number of central station apparatuses, as will be indicated in particularity hereinafter. The structure utilized in affording this feature of switching control has associated with it supervisory indicating lamps so that in addition to serving as a switch board, this apparatus also constitutes a traffic index or guide.

Incidental to another feature of the present invention there is provided a message carrier routing apparatus consisting of a magazine and hopper unit associated with each tape perforating receiver mechanism whereby the carriers, as they are loaded with message tapes and then discharged, are deposited and stored in individual chutes predetermined as to destination. Thereafter, as the belt conveyor is advanced by continuous operation and certain storage portions or compartments thereof pass beneath the vicinity of those chutes, means are provided for automatically discharging the containers from said chutes, so that they will be precipitated and be received in the particular conveyor compartment which, together with other message containers also there, are routed to the same destination transmitter. Thereafter, when the particular compartment advances to the proximity of the

particular transmitting apparatus associated with the destination line, means are provided whereby all of the containers of that compartment are discharged in orderly manner thereinto and thereafter placed into position for advancement and retransmission, which functions are automatically executed by special means provided at said apparatus.

For a more comprehensive understanding of the details of the present invention, reference may be had to the accompanying drawings and to the particulars of the following specification, wherein like reference characters designate corresponding parts throughout and wherein:

Fig. 1 is a circuit diagram featuring an interchangeable control and index panel through which any one or more of the tape perforating and storage machines may be operatively associated with predetermined compartments of the conveyor and whereby any one of the destination station apparatuses may be likewise predeterminedly associated therewith;

Fig. 2 is a fragmentary side elevation of an installation table showing supports for a conveyor system having incorporated therein certain features of the present invention;

Fig. 3 is an enlarged detail view of certain features of the apparatus illustrated in Fig. 2;

Fig. 4 is a fragmentary sectional view taken approximately on line 4—4 of Fig. 3;

Fig. 5 is a sectional detail view taken approximately on line 5—5 of Fig. 3;

Fig. 6 is an enlarged fragmentary view of a message container distribution hopper;

Fig. 7 is a sectional view taken approximately on line 7—7 of Fig. 6;

Fig. 8 is a schematic diagram illustrating a control circuit arrangement associated with the apparatus featured in Fig. 2; and

Fig. 9 is a diagrammatic circuit illustration of the electric supervising circuit for the operation of apparatus featured in Figs. 2 and 6.

Referring now more particularly to Figs. 2 and 8 of the accompanying drawings, reference character 11 designates an apparatus supporting table located in a central office distributing room and giving support to the vertical journal standards 12 and 13, which carry the driving sprocket 14 and idler 15, respectively. Within the supporting legs of the table 11, there are journaled at 16 and 17, lowermost sheave wheels 18 and 19, all arranged in vertical plane alignment with driver 14 and upper wheel 15. A conveyor belt 21 formed of a suitable flexible material courses about the wheels 14, 15, 18, and 19, as illustrated in Figs. 2 and 8, and under impetus of the driver 14, moves continuously in a counterclockwise direction, advancing its several compartments successively by the various receiving chutes 22 of the transmitter apparatuses or the various discharge chutes 23 of the receiving perforator apparatuses.

Power for operating the conveyor system may be obtained from any suitable prime mover and is distributed through the drive sprocket shaft 24. A driving pinion 25, also carried upon this shaft, meshes with a distributor gear 26, Fig. 3, which is integrally associated upon a shaft 27 with a distributor arm 28 rotating clockwise and traversing as it does so ten segments of a segmented distributor ring 29, so as to bridge successively with its brushes 31 the several segments of ring 29 and the continuous concentric ring 32.

By means of the gear engagements 25 and 26, there is maintained a constant relationship

between the distributor belt 21; that is, its several compartments or spaced divisions located between the partitions 33, and the receiving and discharge throats of the hoppers 22 and 23, as will be explained later.

Cooperating with the belt 21 and the partitions 33 to form a relatively complete enclosure for the contents of the belt compartments, is a rectangularly disposed channel 34 appropriately supported by the framework of the table 11 and forming the internal and side enclosure elements; that is, lowermost in association with the top side of the belt 21, uppermost in association with the bottom side of the belt, and innermost with respect to the side portions thereof. As best indicated in Figs. 4 and 5, the channel 34 is of sufficient width to accommodate the message containing spool 35 snugly but nevertheless freely so that they may be carried without frictional impediment, the belt 21 being of sufficient width to overlie said channel 34 and having feed perforations for meshing with the sprocket teeth 36 of the driver, Fig. 4.

At various points where communication is had with the chutes of the distributors and transmitters, channel 34 is cut out to form suitable openings and at the chutes 22 is supplemented with control mechanism, so that the intaking of spools may be regulated and timed according to the operation of said mechanism. Thus, in Fig. 3, there may be noted at 37 that the bottom wall of the channel 34 is cut out where space is made available to align with the intake throat 38 of a transmitter chute 22. A section of supporting track 39, Fig. 5, is provided to take the place of the support afforded by the channel 34, and this portion of track is integrally associated with a control lever 41, pivoted at 42 and held by a spring 43 in traffic supporting position.

Upon the operation of a control magnet 44 overcoming the influence of spring 43, lever 41 is shifted so as to withdraw the supporting track 39 and to expose the cutout section for permitting those of the containers 35 which pass over the throat 38 to be precipitated into the chute 22.

The lowermost horizontal runner of channel 34 is also cut out, as at 45, Figs. 2 and 6, so as to provide access to the compartments as they pass beneath the storage hoppers 23; but, since this leg of the rectangular channel affords no support, it is not necessary to provide replacement rail sections such as that indicated 39, but instead the channel 34 in the proximities designated 45 is cut away for distances coincident with the lowermost portions of the storage magazines 23.

Each of the magazine hoppers 23 is associated with a tape perforating and spooling unit 46 which may be of the type of apparatus described in the copending application referred to above. As a message is reproduced upon a length of control strip and the prepared form is then placed into a carrier or portage container 35, discharging elements drop the container through the vertical chuteway 47, thence downwardly into an inclined passageway 48, Figs. 6 and 7. Here the container may be permitted to precipitate downwardly on an inclined supporting track made up of consecutive sections 49 normally reclined so as to form a continuous runway for the containers but selectively shiftable into the position such as that occupied by the lowermost one designated in Fig. 6 so as to constitute an obstruction or barrier to the further progress of the carriers 35.

while at the same time exposing a trapdoor escapeway as at 51 for admitting the container thereat downwardly into one of the individual chutes 52 which is predeterminedly assigned to the destination, as will later be described.

Each trapdoor-barrier element 49 is pivoted upon an individual pivot rod 53 and is integrally associated with an actuating gear 54 that meshes with a lever segment 55 pivoted at 56. The normal position of each lever segment 55 is counter-clockwise as viewed in Fig. 6 so that its lowermost extremity overlies the latching shoulder 57 of a bell crank pivoted at 58. When any lever 55 is actuated, it moves clockwise about its pivot 56 under the influence of an individual solenoid 59, which in accordance with the proposed control system, is capable of receiving a momentary energizing impulse, but the operative condition of the lever 55 when placed into its clockwise extreme position is continued because its lowermost extremity becomes lodged behind shoulder 57, as is the condition of the left and lowermost one of the several levers, as designated in Fig. 6.

As a result of this operation, the trapdoor 49 is raised and constitutes a barrier to the further downward progress of any descending container 35. However, after a container 35 enters through the opening 51 exposed by the withdrawn barrier 49 and begins to descend within its selected chute 52, it encounters an inwardly extending pin 61 integrally associated with the latching bell crank of its operated segment lever 55 and causes the camming of it to one side and the consequent counterclockwise rocking or restoration of its bell crank. In this way, the passage by any carrier or container 35 through its selected chute 52 is made to effect the release of its associated trapdoor 49, restoring the normal condition to each magazine 23 when a spool, directed to one of its channels, has arrived at that destination.

In the event that for one reason or another the control apparatus fails to select for operation one of the barriers 49, a spool or container 35 will continue downwardly past all of the barriered channelways 52 until it attains an ultimate discharge channelway 62, which directs such spools through its discharge opening 63 into a reservoir where the spool may be picked up manually and classified or inserted directly into its proper destination channelway 52, whichever is found to be the most expedient disposition to be made.

As the spools or containers 35 descend within the routing chutes 52 of any one of the magazines 23, the first one of them in the order of descent encounters one or the other of two sets of stop pins designated 64 and 65, depending upon the condition at the time of its magnet 68. In each chute both sets of pins are mounted on a single leverage bracket 66, pivoted on a shaft 67 and actuatable by a magnet 68, see also Fig. 7. During the normal, or de-energized, condition of the magnet 68, levers 66 are disposed as the one illustrated in Fig. 7 with its lowermost projecting pins 64 extending into the chute 52 and blocking the downward progress of the spools or containers 35. As the lowermost container 35 is apprehended by the pins 64 and thereat arrested, the pins 65, being at the time retracted, are disposed so as to align horizontally with the space which intervenes between that spool 35 and the second one after a manner best designated in the left-hand chute 52 of Fig. 6.

When, thereafter, magnet 68 is energized, it rocks the supporting lever 66 clockwise, as viewed in Fig. 7, withdrawing the pins 64 but, as it does

so, the pins 65 are inserted to block the oncoming second spool 35, permitting only the lowest one to be discharged through its chute 52 opening at 69. Thereafter, magnet 68 again becomes de-energized and lever 66, which is the armature of magnet 68, is permitted to resume its normal position under the action of its spring, retracting the stop pins 65 and replacing into blocking position the stop pins 64. This operation permits all of the containers 35 to descend the distance of one spool, there having been discharged only one of them into the channelway opening 45 for distribution.

The conveyor belt 21 is preferably divided into a number of compartments each of sufficient size to receive a quantity of containers 35. The ratio between driving pinion 25 and distributor drive gear wheel 26 is preferably such as to allow for the passage by a given point of a length of belt 21, equivalent to one compartment, while brush 28 is traversing one of the segments of ring 29.

Mention has been made above of the transmitting distributor chutes 22 which receive the containers 35 as they are selectively discharged in accordance with the operations of the control magnets 44 associated with each one of the chutes 22. Reference to the copending application referred to above will reveal, concerning the structure of the containers 35, that each is provided with an alignment compelling groove, best indicated at 71, Fig. 3, as a means for guiding the placement of the containers, preparatory to the unwinding of the ribbon coil contained therein. This aligning or guiding notch 71, located 35 on one side of each container 35 is adapted to compel alignment with a key or rib 72, especially provided for this purpose in those conducting tubes and chutes where the critical alignment of the containers is a vital factor to their proper 40 operation.

The transmitting distributor units 73 are apparatuses of this class and, in order that each one of the containers which is dropped into the chute 22 may be brought into alignment, there is 45 provided at each chute 22 a frictionally engaging drive roller 74 pivoted on a shaft 75 which is supported on suitable brackets of the chute housing 22 and driven by a belt 76 from a driving pulley 77 that is carried by the shaft 24. Other 50 chutes 22 having similar equipment to that just described, may be driven by a tandem pulley wheel and belt arrangement from shaft 75.

By means of this arrangement, driving pulley wheel 77, acting through belt 76, causes the friction roller 74 to engage the periphery of each one of the containers 35 and rotate the latter member until the notch 71 is brought into proper alignment with the rib 72. Until this time is reached, a container 35 will be supported upon the upper end of the rib or key 72 so as to be engageable by the friction roller 74 and to be rotated slowly thereby. After the alignment is brought about, a container 35 may no longer receive support from rib 72, but instead will descend properly aligned into the transmitting distributor in position to begin unreeling and signal transmission.

For reference to a disclosure of an automatically fed tape transmitting apparatus 73 that may be employed in connection with the present invention, attention is directed to copending application, Serial No. 505,273, filed October 7, 1943, the features of which are incorporated by reference hereunto.

Attention will now be directed to Fig. 8 wherein

there is disclosed, in conjunction with a schematic illustration of the apparatus featured in Fig. 2, an illustrative circuit arrangement showing how reperforating and transmitting units may be employed in accordance with the present invention to perform the various functions of regulating central station traffic in different types of inter-communication circuits.

In Fig. 8, belt 21, which distributes the containers, encircles the drive roller 14 and idler rollers 15, 18 and 19. The first tape transmitter 13 on the left side of this diagrammatical illustration is connected over wire 18 to a duplex line generally indicated 79. At the distant station 81, the receiving printer is represented by a receiving magnet 82. For transmitting in the other direction, various instrumentalities may be employed. A transmitter of station 81 is represented by transmitting contact 83 and a home recorder by the magnet 84.

The next transmitter 13 of Fig. 8 sends directly over line 87 to a distant station 88 equipped for signal reception only. At 89 there is indicated a transmitter and at 91, a receiver apparatus, in the latter of which the operating shaft is provided with a cam 92. During reception of signals by unit 91, cam 92 continues to rotate, opening the contact pair 93 for intervals of but short duration. When incoming line signals over 102 cease, contact pair 93 remains closed for an extended period. During the intervallic operation of cam 92, slow-to-release relay 94 remains energized and continues to hold its armature 95. After a prolonged de-energization, however, armature 95 is released and in so doing closes a circuit which may include manually controllable switches 96 and 97 for energizing a relay 98 at the transmitter 89. The latter apparatus is designed to be able to operate during the energized condition of relay 98. At other times, the transmitter apparatus is withheld from operation but when relay 98 is energized, signals may be sent out over line 99 to actuate relay 104. The action of relay 104 is to open the circuit between station 106 and 91 at the make-before-break switch 103, thereby supplying a substitute ground for line 102 but causing signal interruptions to become effective upon the 106 station's relay 105.

By means of this arrangement, there is assured that the automatic tape transmitter 89 may not communicate with the destination station 106 during the time in which the latter is transmitting signals over line 102 through the operation of its transmitter contact 107. Thus there are illustrated in this schematic showing several examples of central office service including one of intercontrol between an automatic transmitter unit 89 and a receiving printer and/or tape perforator 91.

There having already been described the structure of the automatically operable discharge chutes shown in Figs. 6 and 7, there will now be explained the features of an illustrative supervisory circuit therefor, Fig. 9, whereby the distribution of storage spools or containers is had without manual execution but instead through the instrumentality of the receiving perforator which is accordingly made to serve as a storage magazine control medium.

In Fig. 9, the reference characters 59a to 59j indicate a series of ten operating magnets which correspond to those designated 59 on Fig. 6. One end of the windings of each of these magnets after passing through an individual resistance connects with the common grounded battery line 115, in 75

which line is located a slow-to-operate relay 116. The other terminals of magnets 59 are connected over individual lines 117 to the armatures 118 of their respectively associated supervisory relays 119a to 119j.

Of the latter ten relays, a common terminal of their several windings is connected through individual resistances with the grounded battery line 121 while their opposite and individually connected winding terminals are associated with the locking contacts 122. Thus, any one of the relays 119 may be energized as by the closure of its supervisory contact pair 123, each of which may be operated coincident with the actuation of an associated selectable pull bar in the receiving device. A momentary actuation by one of the pull bars, though it closes a particular contact pair 123 for but a brief interval, effects the energization and continued operation of its associated relay 119 by reason of the locking circuits traceable from grounded battery at 124, line 121, through the winding of the operated relay 119, contact pair 122, to the common locking circuit 125, release circuit 126, contact pair 127 of slow-to-operate relay 116, to ground.

In this manner, each one of the magazine chute release relays 59a to 59j is made directly responsive to a supervisory relay 119a to 119j which, in turn, responds to the impulse initiated upon the closure of one of the selective pull bars in the receiving apparatus by locking. In order that these selections may not occur except when the result is especially desired, means are provided for making the closure or energization of the relays 59 subservient to several preconditioning devices. Thus, there is provided a relay 128 which may be termed the destination control relay, and its supervisory contact pair 129 which is closed by a special pull bar as a condition preceding the destination selection of any of the other contact pairs 123. Its contact pair 132 is in series with a common ground circuit 131 to which one of the contacts of each pair 123 and 129 is associated parallelly with the others. Also situated in series with the contact pair 132 and before ground is achieved, are the universal bar operated contact pair 133 and a character shift controlled contact 134.

Placement of ground upon common ground circuit 131 is therefore contingent upon the closure of contact pairs 134, 133, and 132. Another pair of control contacts are designated 135 and closed mechanically coincident with an end-of-message signal; that is, after a message has been completed by the recording operator, the pair serves to prepare a circuit for energizing the coiling mechanism at the perforator apparatus. Before this is effective, however, there must also be operated the two contact pairs 133 and 134, the former responding to the receiver universal bar, an operation coincident with each revolution of the receiver driven shaft, and the latter contact pair 134 being controlled by the shift pull bar or its corresponding element. None of the contact pairs 123 may become effective until there has been received a shift signal for the closure of contact pair 134 nor until there has been operated the universal bar contact 133, followed by the destination signal operated contact 129. It will be understood, therefore, that the actuation of any contact pair 123 at any time other than that following the succession of the preparatory signals afore-described will have no effect upon the routing selector relays 119 and their operating magnets 59.

Coincident with the receipt of the end-of-mes-

sage signal whereupon contact pair 135 is closed, a circuit is completed which is traceable from the ground supplying shift contacts 134, universal element contact pair 133, contact pair 135, line 137, relay 138 to grounded battery at 136. Relay 138, which is thus energized, is a supervisory start electromagnet which initiates the tape spooling device described in the afore-mentioned copending application and in the copending application, the relay is designated by the reference character 49. In accordance with a preferred form of operation, this is followed by an energizing impulse for the destination relay 128 which will lock through its contact pair 139 and the grounded shift contact pair 134 and so remain until an unshift signal is received for opening contact pair 134.

The winding arbor of the spooling machine is designated cross-sectionally in Fig. 9 at 141. This shaft, whose full cycle of revolution coincides with the complete winding of a message upon the mandrel of said machine, is here shown with an additional cam for actuating a contact pair 142. Towards the completion of its cycle, this cam of shaft 141 engages a follower and through its closure of contact pair 142, there is caused to be energized a slow-to-operate relay 143 over an obvious circuit effecting thereby the closure of a further contact pair 144.

As a result of the closure of contact pair 144, ground is placed upon the common line 145 which connects parallelly with one of the contacts of each relay controlled contact pair 118, afore-described. This completes the circuit, one of the relays 118 upon energization having prepared it, to one of the magazine chute selecting relays 59a to 59j, and in response to this function, a barrier plate 49, Fig. 6, associated with said relays 59 is raised into vertical or selecting position, thereby determining the magazine channel 51 into which the particular spooled message will be directed. Relay 143 is made slow to operate, in order to obtain the delayed selection of a routing relay 59 because there may be a possibility that a previously discharged spool has not yet arrived at the selecting chute 23 of a storage magazine.

As relay 138 corresponds to the start magnet or relay 49 indicated in Fig. 3 of the afore-mentioned copending application so relay 147 corresponds to the companion magnet or relay 118 illustrated thereat. In the tape spooling apparatus there is provided a probing arm which, following the termination of a spool winding operation, senses for the end of the tape and upon encountering this condition permits a contact pair thereat indicated 115 to close. This contact pair is designated in Fig. 9 by the reference numeral 148.

Accordingly there is disclosed in this illustration a manner of supervising the destination for delivery of spools which contain messages following their release from a spooling machine such as that illustrated in said copending application and preparatory to their being discharged onto a conveyor belt. Magnets 59, preferably being ten in number, are designed to accommodate a storage magazine of the type illustrated in Figs. 6 and 7 having ten discharge chutes 52, in addition to the unclassified discharge chute 63.

Each channel or chute of the storage magazine, Figs. 6 and 7, is capable of retaining a quantity of spools between the lowermost points where they are held by the pair of retaining pins 64 and the level at which they may not interfere

with the proper closure of their associated barrier or trapdoor 49. Meanwhile the conveyor belt 21, continuing its cycle under impetus of the apparatus disclosed in Fig. 2, presents successively its compartments to the several discharge openings 69 of the various storage magazines. Upon the operation of any magnet 68, one of the spools thereat withheld by the pins 64 is discharged and this performance is accomplished in a characteristic manner; that is, in accordance with a predetermined plan so that the entry of the spool will be made into a particular compartment of the conveyor belt 21 destined to be discharged at a particular station for retransmission.

Fig. 1 illustrates a wiring diagram of a control board which may be utilized for properly associating the performance of the several magazine discharge release magnets 68, in relation to that of the magnets 44, Fig. 5, which serve to release the spools from the belt compartments into destination transmitter channels 22.

For purposes of convenient differentiation and in so far as the conveyor itself is concerned, the discharge magazines may be referred to as loading stations while discharge chutes 22, which are associated with tape transmitters and unwinding machines, may be referred to as discharge stations. Within this contemplation the reference character 151, Fig. 1, designates generally a loading station control circuit supervisory switchboard while the reference character 152 designates a corresponding control circuit switchboard for supervising the discharge apparatus which too is provided with means for varying the association of different compartments of the conveyor belt with different discharge chutes of the transmitter equipment. In Fig. 1, the rotary distributor apparatus of Fig. 3 is indicated at the lower left-hand corner of the wiring diagram and the brush carrier 28 is thereat designated as sweeping over a segmented ring 29 and connecting its segments successively with a continuous solid ring 32. Each segment of ring 29 is electrically associated with a bus bar 153a to 153j.

At each station, connecting lines 154 associate each one of the bus lines 153 with a particular one of a series of ten terminal screws designated 155. In the junction block 156, each terminal screw is located opposite an associated terminal screw 157 but the electrical connection between terminal screws is not necessarily in correspondence with their opposite alignments. Instead the association between terminal screws 155 and 157 may be had in accordance with any predetermined arrangement and thereby is established the release period in terms of sequence as rotary brush 28 traverses the segment of ring 29 routing impulses over the branch lines 154.

Connected to the opposite terminals 157 are local bus lines 158, each one of which extends across the switchboard 151 and is connected to the upper contact members 159 of ten pairs of contacts which may have the form of conventional connector jacks that may be brought into electrical communication with each other upon the insertion of an electrically conductive plug (not shown).

The other contact points of each pair of contacts 159 are connected horizontally to the common bus lines 163 and each of these over a line 161 and thence through the windings of one of the spool release magnets 68a to 68j, the opposite terminal of whose windings are connected together over a line 164 to grounded battery at 162. Accordingly, with the insertion of a con-

necter plug in any one of the jacks, that is, the contact pairs 159, a circuit is completed traceable from one of the bus lines 158 through the particular contact pair having the inserted plug, thence over a horizontal bus line 163, individual circuit 161, through the winding of an associated magnet 68a to 68j to grounded battery at 162. At a critical instant when the distributor brush 28 is traversing the segmented ring 29, therefore, an impulse originating at battery 162 is traceable through the winding of one of the magnets 68a to 68j to ground at the collector ring 32 of the distributor. This will cause a spool to be released and to descend through its discharge opening 69 into one of the compartments of the belt 21.

While the relationship between the segments of ring 29 and their related compartments in belt 21 may be regulated through the gearing ratio between pinion 25 and driven gear 26, as explained in connection with the description of Fig. 3, the arrangement of transmitting and perforator-printing devices at the central station office as related to the table 11, Fig. 2, may not be so conveniently adjustable. In other words, the disposition of apparatus upon the table 11 may not be always feasible in such a manner as to correlate the operation of release magnets 68 and 44 with the progress of belt 21. Accordingly, means is provided whereby the functional response of its related magnet 44 or 68 may be attuned to the particular cycle of the distributor belt 21 regardless of the location of each instrument with respect to said belt and also with respect to other instruments on the table 11.

A first regulation may be attained by bringing the belt to rest at any particular position with a discharge tube opposite a predetermined compartment in the belt 21. Thereafter, a plug may be inserted in a related jack 159 which will connect the segments on ring 29 then engaged by the brushes 31 whose associated compartment is then opposite the discharge tube with the release magnet of the particular tube. This particular flexibility of adjustment alone is not sufficient to take care of all conditions, however, since under conceivable circumstances, another discharge tube may at the same instant be in alignment with its compartment in the belt 21 in which the discharge is desired at a particular moment. To accommodate for this contingency which may arise, there is provided the junction block 156 having the cross terminals 155 and 157, the internal connection between which may be bridged as indicated in dotted lines on Fig. 1, in connection with the terminal block 156.

In the illustration of a discharge station 152 whose related switching apparatus is generally identical with that of the loading station 151, a junction block 165 is thereat indicated having the opposite terminal screws 166 and 167 after the manner of terminal screws 155 and 157, but in contradistinction thereto there is shown an arrangement of hooking up terminal screws in such a manner as to associate more than one of certain terminal screws of the class 167 with single ones of the terminal screws 166 and in reverse manner more than one of the terminal screws of class 166 may be electrically associated with single ones of the terminal screws 167. In accordance with this arrangement, there is illustrated a manner of operation whereby in discharging from the conveyor belt 21 onto the transmission chutes 22, several compartments may be made to discharge into a single chute.

There will be noted at 194 and 195, Fig. 8, two

rows of supervisory indicating lamps, the former of which are connected over individual circuits 196 with control contacts 197 situated so as to be operable by a magazine telltale lever 198 which, as each one of the carriers 35 is dropped through a chute 52, causes the closure of the contact pair 197 and a consequent completion of a circuit 196 lighting a lamp 194 for a brief period. The frequency of flashes will give an indication of the amount of traffic in that particular route. Whenever the chute receives an accumulation of carriers, the contacts 197 will be closed continuously and light the lamp 194 continuously, thus indicating to the traffic clerk that it may be necessary to start a new circuit or to reroute some of the traffic.

The index lamps 195 are connected over individual lines 199 to the back contacts 201 of the line relays 79 and these lamps 195 will flicker in accordance with the signal impulses received by the relays 79 designating in a reverse manner each signal. The placement of the lamps 194 and 195 may be made close to their related jacks 159 in order to be identified with the proper circuits and when any one of the chutes 52 becomes full, a continuous lighting of its associated signal lamp 194 will apprise the operator of this fact so that he may relieve the load from ones of the receiving apparatuses in favor of others which may at a particular time be idle.

Thus, there is described a system of perforated control form distribution having in mind a plurality of tape preparing stations and a plurality of tape transmitting destinations with totally automatic intervening means for transferring tape which is prepared at incoming distribution stations and routed through an automatic conveyor apparatus to a plurality of retransmitting stations. There is thereby utilized efficiently all of the available line time of certain destination stations through a control of the distribution. Through the wiring arrangement illustrated in Fig. 9, the discharge of coiled tape messages which have been placed into cylindrical containers 45 may be regulated so as to be dropped into proper ones of a series of chutes in a storage magazine, Figs. 6 and 7. Thereafter these spools are released from their respective chutes in said storage magazine by the selective energization of release magnet 68 and received in compartments of an endless conveyor belt 21, which compartments are destined to discharge into predeterminedly arranged ones of a series of transmitting device chutes 22, Fig. 8. From this point, the messages 55 contained on the spools are successively transmitted over the particular lines associated with said transmitting apparatus 73 until the chutes 22 are emptied.

While the present invention has been illustrated and described with reference to particular contemplations of embodiment, it will be understood, nevertheless, that numerous variations and modifications may be made without departing from the essential spirit or scope thereof. Accordingly, it is not intended to be limited by the specific language of the foregoing detailed description nor by the particular features shown on the accompanying drawings except as indicated in the hereunto appended claims.

What is claimed is:

1. In a signaling system, a plurality of incoming lines, a plurality of outgoing lines, means for preparing control forms under the supervision of signal messages received over said incoming lines, means for transmitting signal messages over said

outgoing lines in accordance with the performances on prepared control forms, a conveyor and automatic routing means responsive to destination signals contained on incoming line messages for delivering perforated control forms on said conveyor to particular ones of said transmitting means of said outgoing lines.

2. In a message handling system, an endless conveyor for traveling over a route, an apparatus supporting table parallel to the sides of said route, a plurality of receiving perforators and tape transmitters supported on said table including discharge chutes from said route connecting said conveyor with said transmitters and receiving chutes connecting said reperforators to said conveyor and means to cause the messages to be discharged through predetermined of said discharge chutes to said conveyor and through predetermined of said receiving chutes from said conveyor.

3. In a message distributing system, an endless conveyor having a plurality of distribution compartments, a storage magazine comprising an inclined runway having communication with a series of parallel storage chutes, selective barriers movable from a supporting position to a deflecting position for directing message carriers from said runway into predetermined ones of said chutes, and releasing means individual to each of said chutes for discharging said message carriers from said chutes into predetermined ones of said compartments, said discharge into certain compartments being dependent upon which of said storage chutes said message carriers were directed into.

4. In an automatic control system, means for variably associating a plurality of discharge devices with conveyor compartments comprising, in combination, a series of electromagnetic release means each associated with one of said discharge devices, a cyclically operative distributor having release segments timed to accord with successive compartments of a conveyor, a plug board, and electrical connecting means established by said plug board for variably associating the segments of said distributor with different ones of said electromagnetic release means.

5. In combination with a plurality of tape perforating machines, apparatus for distributing the tape following its preparation comprising means for packaging said tapes within carriers, a series of discharge chutes leading from each of said machines, a plurality of deflecting elements for directing the passage of a carrier from any of said machines to a particular discharge chute, and means responsive to a portion of the message similar to that installed on said perforated tape for preparing one of said deflecting elements for subsequent operation when its carrier is released to said discharge chutes.

6. In a telegraph system, a traffic distribution station having a plurality of communication circuits, apparatus responsive to signals over said circuits for preparing and packaging a control form, apparatus operated by said form for transmitting signals over said circuits, and means controlled by certain of the signals received over said circuits for causing said prepared and packaged forms to be routed from their preparing and packaging apparatus to a selected transmitting apparatus.

7. In a sorting system, a plurality of stations each having apparatus for preparing a form with destination signals and message signals, a conveyor for transporting a form to any one of a series of destinations, and means associated with

5 said conveyor and under the control of said destination signals for discharging the forms from said conveyor at corresponding destinations.

8. In a supervisory traffic control system, a plurality of loading stations, a number of chutes at each of said stations, a number of destination stations, a plug board, and electrical control means established by said plug board for interchangeably associating certain of said chutes with any of said destination stations.

9. In a telegraph traffic control system, a plurality of machines for preparing transmitting tape, a plurality of transmitters operable by said tape, means under the control of an electrically adjustable traffic board for routing prepared tape from said preparing machines to said transmitters in accordance with information carried by the tape, and signal lamps associated with each of said transmitters for denoting the volume of traffic borne thereby.

10. In a telegraphic system, a telegraph circuit, a receiving device controlled by signals received over said circuit and adapted to prepare unit pieces of record material each bearing a record of the signals appertaining to a single message, a plurality of destinations for said messages, conveyor means to carry a unit message to any one of said destinations, and means controlled by signals accompanying each unit message to determine the particular destination to which said message is delivered.

11. In a control system, a plurality of items to be transported, a conveyor for said items, a plurality of loading stations adjacent said conveyor, a plurality of destination stations adjacent said conveyor, means to discharge an item at any destination station, control means at a central point for controlling the loading at all said loading stations and the discharge at all destination stations, and means including a plug board included in said central control means to quickly alter the control at any loading station or the discharge at any destination station.

12. In a carrier system, a plurality of containers, a stationary container receiving reservoir, a plurality of compartments in said reservoir each capable of receiving containers, means to deliver containers to said reservoir, a gate at the entrance to each compartment, means to open a particular gate according to the destination of a container placed in the reservoir, a series of travelling compartments, a second gate in each stationary compartment intermediate said first-mentioned gate and a discharge outlet of said compartment, and means to open said second gate at an appropriate time to discharge the contents of said stationary compartment into a selected moving compartment.

13. In a carrier system, a plurality of containers, a stationary container storage reservoir, said reservoir including an entrance compartment and a plurality of secondary compartments, a plurality of container receptacles, means to move said receptacles in succession past the discharge outlets of said secondary compartments, a gate between said entrance compartment and each of said secondary compartments, means to deliver containers to said entrance compartment, means to open said entrance gates selectively according to the destinations of said containers, and means to delay the discharge of said container from said secondary compartment until a selected receptacle is opposite said corresponding discharge outlet.

14. In a telegraph system, a plurality of signal

transmitting devices, a plurality of signal controlled devices for preparing control forms adapted to control said transmitters, a power-operated conveyor means for carrying said prepared forms from said form preparing device to a transmitting device, and means included in said preparing device and controlled by the received signals for selectively controlling said conveyor to deliver said form at a transmitter corresponding to the destination of said form.

15. In a telegraph system, a receiving instrument for preparing messages, each message being recorded on an individual piece of record material, a transmitter adapted to receive said pieces of material and to be controlled thereby, and means including a conveyor entirely automatic to selectively transfer said record material from said preparing device to said transmitter in condition to control said transmitter.

16. In a telegraph system, a receiving device adapted to prepare control forms on unitary pieces of record material, a plurality of transmitters adapted to receive and be controlled by said control forms, conveyor means to receive said completed forms and deliver them to a particular transmitter, means adjacent to said transmitter to receive and locate the form for transmitting signals under the control of code marks thereon, and signal controlled means to select for each control form the particular transmitter to which it is delivered.

17. In a routing system, a series of chutes, a gate at the entrance to each chute, a gate between the entrance gate and the discharge outlet of said chutes, means to open said entrance gates one at a time in succession in sequence, varying sequence according to the destinations of successively received items, and means to open the discharge gates in an invariable sequence according to destinations assigned to the chutes.

18. In a retransmission system, a plurality of receiving lines, a plurality of transmitting lines, means for preparing a control form under the supervision of signals received over one of said receiving lines, means for transmitting a message in accordance with the preparations on said control form over one of said transmitting lines, and automatic means including a conveyor responsive to some of said signals received over said incoming lines for selectively directing said prepared control forms to said retransmitting means whereby said messages are transmitted over selected transmitting lines.

19. In a retransmission system, apparatus responsive to incoming line signals for making corresponding perforations on a control form, a conveyor for routing the control forms, a plurality of discharge stations adjacent said conveyor, and means responsive to some of said incoming line signals for causing said control forms to be discharged predeterminedly from said conveyor at some discharge stations.

20. In a retransmitting system, a plurality of lines for receiving unit messages each composed of routing, text, and end of message signals, a plurality of lines for transmitting said messages, means for preparing a control form under the supervision of said unit message received over one of said receiving lines, means for transmitting a message in accordance with the preparations on said control form over one of said transmitting lines, automatic means including a conveyor conditioned by said routing signals received over said incoming line for selectively directing said prepared control form to one of said transmitting means, and means responsive to said end of message signal for determining when said automatic means will become effective.

21. In a retransmission system, a plurality of stations for receiving incoming code signals and preparing a control form for each unit message, a loading station associated with each of said receiving stations, a plurality of stations for transmitting said unit messages under the control of said control forms, a discharge station associated with each of said transmitting stations, a conveyor, and means responsive to some of said incoming code signals for selectively routing said control forms over said conveyor whereby said control forms may originate at any of said loading stations and be routed to any of said discharge stations.

22. In combination with a continuous conveyor system, a plurality of loading stations, a plurality of discharge stations, a plurality of chutes at each of said loading stations, means for automatically delivering articles to said loading stations and routing them predeterminedly into one of said chutes, means associated with said conveyor to discharge said articles at one of said discharge stations in accordance with the nature of the chute through which it was routed, and switchable means for variously associating said chutes with any of said discharge stations to suit periodic changes in traffic conditions.

LOUIS M. POTTS.
